UNITED STATES PATENT OFFICE.

CHARLES ARTHUR CHAPMAN, OF HORLEY, ENGLAND, ASSIGNOR TO
ALFRED WARREN AND CHARLES FIPPARD, OF SAME PLACE.

SPRING-SEAT.

SPECIFICATION forming part of Letters Patent No. 610,960, dated September 20, 1898.

Application filed September 20, 1897. Serial No. 652,405. (No model.) Patented in England March 26, 1897, No. 7,866; in France August 12, 1897, No. 269,562, and in Austria September 6, 1897, No. 47/3,263.

To all whom it may concern:

Be it known that I, CHARLES ARTHUR CHAPMAN, a subject of the Queen of Great Britain, residing at Glenthorne, Horley, in the county 5 of Surrey, England, have invented certain new and useful Spring-Seats, (for which I have received Letters Patent in Great Britain, No. 7,866, dated March 26, 1897; in Austria, No. 47/3,263, dated September 6, 1897, 10 and in France, No. 269,562, dated August 12, 1897,) of which the following is a specification.

This invention relates to spring-seats especially suitable for the saddles of cycles.

15 The saddle consists of front and back plates connected by springs which form the seat, each plate being supported by a curved bar having one or more knuckle-jointed hinges in it so arranged that the ends cannot be 20 turned upward beyond a certain point by the tension of the springs, but can be turned downward by pressure, so further stretching the springs.

Figure 1 is a vertical central section. Fig. 25 2 is a plan; and Figs. 3 and 4 are transverse sections on the lines 3 3 and 4 4, Figs. 1 and 2, looking to the left and right, respectively. Fig. 5 is a local section on the line 5 5, Fig. 1.

a and *b* are the back and front plates, carried by arms *a'* and *b'*, fixed to them and pivoted, respectively, at *a²* *b²* to the flanges *c' c'* of the plate *c*. The four corners of each flange *c'* are turned outward, forming stops *c²*, which limit the movement of the arms *a'* and *b'*. The plate *c* rests on a plate *d*, the flanges *d'* of which are notched and rest on the usual bar-support *e*, the whole being secured by the eyebolt *f* and nut *f'*.

g is an india-rubber cord covered with braid-

ing and laced around pulleys *h* on the plates 40 *a* and *b*. The pulleys *h* on the plate *a* are arranged on the under side thereof near its inner edge. The drawings show eight such pulleys arranged in a curved line beneath the plate. The pulleys *h* on the plate *b* are arranged as indicated in Fig. 4. One pulley at 45 the top of the U-shaped frame is arranged on a vertical axis. The other pulleys are arranged in vertical series on horizontal axes, each horizontal shaft bearing two pulleys. 50 The peak is covered with leather *j*, and the seat may also be covered with soft leather or other material.

The details of construction may be varied without departing from my invention; but 55 the parts *g* should be elastic or stretchable, and one at least of the arms *a'* or *b'* should be pivoted.

I wish it to be understood that I do not claim, broadly, a saddle having a seat consisting of stretched springs; but

What I claim is—

1. In a saddle, the combination of front and back plates, supports for the plates, a joint between the supports so that the plates 65 can move apart, pulleys pivoted to the plates and springs placed around the pulleys.

2. In a saddle, the combination of front and back plates, supports for the plates, pivots for the supports, stops limiting the travel 70 of the supports, pulleys pivoted to the plates, and india-rubber cord laced around the pulleys.

CHARLES ARTHUR CHAPMAN.

Witnesses:

WILFRED CARPMAEL,
W. M. HARRIS.
